UNITED STATES PATENT OFFICE

HARRY T. WANDLING, OF ALTON, ILLINOIS

STOKER LINK

Application filed February 24, 1932. Serial No. 594,919½.

This invention relates to certain new and useful improvements in stoker links, the peculiarities of which will be hereinafter fully described and claimed.

5 The main objects of my invention are to provide means for producing first, a self-cleaning link; second, a free discharge of the accumulated dirt from the eyes of the link; third, a non-gripping engagement of each eye of said link with its pivot rod; fourth, a reduction of frictional engagement between the eye and its rod; fifth, continued flexible mounting of the links on their pivot rods; sixth, practical avoidance of danger of fracture of the links in flexing; and seventh, reduction of operating power required to pull a stoker chain grate when composed of my links.

20 In the usual form of stoker links, the circular eyes of such links connected by their pivot rods, become stiff and rigid on the rods from deposit of waste dirt or semifluid material from the active grate surface above them. The heat of combustion bakes such accumulated waste dirt during the twenty or thirty minutes that the links are passing from the front to the rear of the stoker, and often cements the rods in the eyes so that when the links reach the rear roller they are in stiff 25 and rigid engagement with the rods, and will not flex to pass around the rear roller without considerable exertion of pulling force to restore their pivotal engagement. This often results in fracture of the links in the middle or in the eyes, and always requires greater pulling power than if the original flexible engagement of the links and rods was substantially maintained.

30 My improved form of link practically overcomes the above difficulties by means now to be described.

In the accompanying drawing in which like reference numerals indicate corresponding parts,

45 Fig. 1 represents a side view of my improved stoker link;

50 Fig. 2, a section on the line 2—2 of Fig. 1, looking upward;

55 Fig. 3, a side view of several of my links

alternately arranged on their pivot rods in a chain grate stoker; and

Fig. 4, a bottom plan view of the same.

Referring to the drawing, the numeral 1 designates the top of a stoker link of any suitable construction, having a comparatively thin central web 2, with eyes near the ends for pivotal mounting on transverse pivot rods 4.

These eyes are preferably horizontally 60 elongated more or less, towards the center of the link, or otherwise cut away slantingly from the usual cylindrical bearing construction, so as to form bearing surfaces 5 of substantially semicircular shape at their opposite extreme ends, for flexible engagement 65 with opposite sides of adjacent rods mounted therein. The unoccupied open spaces or cut away bearing portion 6 of said eyes are adjacent to each other in each link, in normal operative position of the stoker grate formed by multiple links mounted on their pivot rods, which rods are disposed normally at the opposite ends of said eyes as the grate is pulled along in an endless chain with the superposed bed of coal or other material, by the usual driving sprockets (not shown) in the 70 usual manner.

These semicircular end bearing surfaces are widened by similar hubs projecting laterally from the web of the link, but one or both sides of the hubs are cut away slantingly at 3 to substantially the thickness of the web at said open spaces, as shown in the bottom plan, Fig. 4. When the lower hub portion 75 only is cut away, the remaining upper portion 5' shields said open space like a hood from the sifting material, when traveling in the upper row of the grate, but during the return travel in the lower row this hood would become a pan and collect material thereon which would tend to bind the links on the rods and obstruct their pivotal action while passing upward around the front sprockets into the upper row. I therefore cut away this web above 80 and below the open end of the eye from substantially the vertical central plane through the rods towards the center of the link as shown at 3 in the figures, and thus avoid 85 forming a pan when the link travels in the 90 upper row.

95

100

lower row of the grate. Such a pan is provided by a prior link which has a portion of its elongated eyes cut away at the lower side only. My construction therefor promotes 5 flexibility of the link in passing around both the front sprocket and the rear roller, and secures greater efficiency in operation.

The wide hubs space the links laterally on 10 the pivot rods connecting them, and thus provide suitable clearance spaces between the tops of the links for 26% or other desired percentage of draft openings. The links thus connected form longitudinal strands in which 15 the links in each strand alternate with those in adjacent strands, as indicated in the drawing. The semicircular end bearing surface in each link engages the opposite side of the rod from that engaged by adjacent eyes.

Thus the rods are centered as usual, though 20 only half the usual bearing surface is provided in each eye, and the frictional leverage of clogging material is reduced accordingly.

In my form of link therefore, the waste 25 dirt sifting into the elongated, or otherwise cut away eyes, is afforded only a semicircle for deposit in each eye, and such accumulated material is readily discharged into the adjacent open space 6 when the link is flexed in passing down over the usual rear roller. 30 The danger of gripping is practically avoided, and the bearing is self-cleaning.

The comparatively narrow width of the web above and below the said open space allows the material that is discharged from the 35 flexed bearing to fall out when passing the front sprockets or the rear roller, or when the link is traveling in either upper or lower row of the grate, and the open semicircular engagement of my bearing is readily flexed, 40 and is non-gripping as compared with the usual circular eye bearing or one that is partially open. The consequent reduced power required to flex links of my form, and the greatly lessened danger of fracture, are evident. 45 In my form, the waste dirt that may enter my semicircular bearing has not the frictional leverage on the rod possessed by the larger circumferential area of the usual circular eye, and the open space 6 adjacent the 50 rod also affords full opportunity for discharge of accumulated material, in any position of the link.

I do not limit myself to the construction shown, except by the appended claims.

55 I claim:

1. A stoker link comprising a web having horizontally elongated eyes provided with lateral webs forming semi-circular bearing surfaces at their outer ends, and cut away 60 above and below the adjacent ends of said eyes from substantially the ends of said semicircular bearings towards the center of the link substantially as described.

2. In a chain grate stoker having links piv- 65 otally mounted in upper and lower

transverse rods, a series of links having elongated eyes with lateral webs forming semi-circular bearing surfaces at the outer ends of said eyes on the transverse rods, said webs being cut away above and below the eyes from substantially the vertical central plane through said rods towards the center of each link, thereby providing free discharge of material entering the adjacent open portions of said eyes when said links are disposed in either upper or lower rows of the grate.

In testimony whereof, I have affixed my signature.

HARRY T. WANDLING.
